UNITED STATES PATENT OFFICE.

CLAUDE R. SILVERS, OF PERU, INDIANA, ASSIGNOR OF ONE-HALF TO
ALPHEUS J. HEAVNER, OF SAME PLACE.

DESIGN FOR A HOLDBACK-IRON.

SPECIFICATION forming part of Design No. 34,487, dated May 7, 1901.

Application filed March 11, 1901. Serial No. 50,769. Term of patent 14 years.

To all whom it may concern:

Be it known that I, CLAUDE R. SILVERS, a citizen of the United States, residing at Peru, in the county of Miami and State of Indiana, have invented and produced a certain new and original Design for a Holdback-Iron; and I do declare the following to be a full, clear, and exact description of the invention, such as will enable others skilled in the art to which it appertains to make and use the same.

The invention relates to a new and original design for a holdback-iron; and it consists of a design of the shape and configuration shown in the accompanying drawings, in which—

15 Figure 1 is a bottom perspective view, and Fig. 2 is a longitudinal sectional view.

The essential features of the design are set forth in the following description:

1 represents a thin, flat, and comparatively wide bar formed at one end with a flattened enlargement 2, conforming to the width of the bar, but increasing the thickness at that end of the bar to approximately double the thick-

ness of the body of the bar. A slot or eye 3 extends laterally through the enlarged end 25 of the bar and obliquely to the length of the bar. The top and bottom walls 4 and 5 of this slot are flat and disposed in parallel planes. At its inner obliquely-extending end 6 the enlargement 2 curves downwardly and 30 gradually vanishes into the plane of the upper surface of the body of the bar. The outer end 7 of the enlarged portion of the bar also extends obliquely to the body of the bar and is curved or rounded off at its upper edge, as 35 shown.

What I claim is—

The design for a holdback-iron as herein shown and described.

In testimony whereof I have hereunto set 40 my hand in presence of two subscribing witnesses.

CLAUDE R. SILVERS.
